ROTARY DISK BIT

James W. Sperry, South Pasadena, Calif.

Application August 19, 1929, Serial No. 336,847

9 Claims. (Cl. 255—71)

This invention relates to rotary well drilling equipment and relates particularly to a rotary drilling bit in which the cutting edges are formed on circular blades or disks which revolve during

5 the cutting operation, thus bringing consecutive portions of the cutting edges into cutting engagement with the earth structure being penetrated.

It is an object of the invention to provide a 10 disk bit having a plurality of cutting disks mounted in rotatable manner on bearing members which are secured in an integral body structure having downwardly extending legs or fingers of rugged character in which the bearing 15 members are held and securely locked in position in such a manner that they will not become loosened and displaced during the drilling operation so as to cause loss of steel parts of the drill bit in the hole.

20 A further object of the invention is to provide a body with a plurality of downwardly extending legs, between which legs channels are formed, bearing members for disk cutters placed between the legs in the channels formed thereby, and pin members extending through the legs and the bearing members for holding the bearing members securely in position in such a manner that they cannot come loose and be lost with the cutters in the well.

25 A further object of the invention is to provide a bit of this character having a plurality of cutting disks operating in adjacent positions but being so supported that they will rotate on disaligned axes, thereby producing an action 30 which will cause a very thorough mixing of the cuttings into the rotary mud which is delivered into the zone of the cutting operation through discharge openings in the drill bit.

35 A further object of the invention is to provide a drill bit of this character having a body with outlet or discharge openings for rotary mud, these openings being so placed that the rotary mud will be directed against the cutting edges of the disk cutters employed in the bit.

40 A further object of the invention is to provide a new locking means for pins or bolts employed in drill bits, which locking means is so formed that a rigid and positive holding of the pins, bolts, or shafts is accomplished.

45 Further objects and advantages of the invention will be set forth in the following part of the specification.

Referring to the drawing which is for illustrative purposes only,

50 Fig. 1 is an elevational view showing a simple

embodiment of my invention attached to a sub having reamer elements, this entire assembly being adapted for attachment to the lower end of a string of drill pipe.

Fig. 2 is a side view of the lower end of the 5 drill bit shown in Fig. 1 derived as indicated by the arrow 2 therein.

Fig. 3 is a partly sectioned view of the lower 10 end of the drill bit showing the manner in which the disk bearings are secured in place in the bit body.

Fig. 4 is a cross section on a plane represented by the line 4—4 of Fig. 3.

Fig. 5 is an enlarged fragmentary sectional 15 view showing in detail a modified form of locking device and further showing the use of a single pin for holding the bearing member of a small disk bit.

Fig. 6 is an elevational view showing the 20 threaded end of the pin illustrated in Fig. 5.

Fig. 7 is an enlarged elevational view showing 25 the locking means which appears in section in Fig. 5.

A simple embodiment of my invention disclosed in Fig. 1 includes a body 11 of cylindrical form, but flattened on the sides thereof as indicated at 12, having projecting downwardly therefrom a central leg 13, intermediate legs 14, and outer legs 15. The adjacent faces of the legs 13, 14, and 15 are preferably flat and 30 parallel in order that the inner and outer spaces or channels 17 and 18 will be defined by flat parallel walls 19.

For purpose of attaching the bit to a operating 35 drilling structure, the upper end of the body 11 is provided with an internally threaded recess 20 in which a threaded pin 21 of a sub 22 or other tool joint part may be screwed.

The sub 22 has a threaded tool joint pin 23 projecting upwardly therefrom in the manner 40 shown, which may be threaded into a tool joint box on the lower end of a string of drill pipe which extends downwardly within a hole being drilled and is rotated by rotary drilling mechanism situated in the derrick of the drilling 45 equipment, all of which is well known to the rotary well drilling art and therefore will not be further discussed herein. The sub 22 is provided with reamer element 24 which are preferably in the form of reamer rollers retained in 50 the customary manner in suitable recesses 25 of the sub 22.

As shown best in Figs. 3 and 4, bearing members 27 for inner cutter disks 28 are secured in 55 the inner channels 17, and bearing members 29

for outer cutter disks 30 are secured in the outer channels or faces 18. The bearing members 27 and 29 are of cylindrical form, and the cutters 28 and 30 are bored to fit the circumferential faces 31 of the bearing members 27 and 29 somewhat loosely so that the cutters 28 and 30, which are of less width or thickness than the spaces or channels 17 and 18, may have a wobbling action on the bearing members 27 and 29.

10 In larger bits of my invention the bearing members 27 and 29 are secured in place by pairs of pins 32 and 33, one pair of pins 32 and 33 projecting inwardly through each of the outer legs 15, through the adjacent intermediate leg 14, and making threaded engagement at 34 with the inner leg or central leg 13, as shown in Figs. 3 and 4. The right-hand pair of pins 32 and 33 and the left-hand pair of pins 32 and 33 are each respectively located forwardly of a central or diametral vertical axis A—A in the direction of rotation of the bit, as indicated by the arrow 36 of Fig. 4, in which the right-hand and left-hand pairs of pins 32 and 33 are shown located respectively on the vertical planes B—B and C—C which lie parallel to the diametral plane A—A.

15

20

25

Therefore, the threaded inner ends of the pins 32 and 33 engage the central leg 13 at points on either side of a central discharge opening 37 which extends vertically through the central leg 13 so as to deliver mud or drilling fluid from a counterbore 38 formed at the lower end of the threaded recess 26 to the zone of the drilling operation adjacent to the lower edges of the cutters 28 and 30. The forwardly offsetting of the pairs of pins 32 and 33 in the manner previously described is for the purpose of causing the cutter disks 28 and 30 to project laterally from the bit structure in the direction 40 of rotation of the bit so that the cutting action will be confined to the forward portions of the cutting edges as indicated at 39 and also to the lower portions of the cutting edges which are in engagement with the bottom of the hole.

45 As will be noted, the inner cutting disks 28 are of smaller diameter than the outer cutting disks 30, but the lower portions of the cutting edges provided by the inner disks 28 are nearly in horizontal alignment with the lower portions of the cutting edges provided by the outer disks 30, this resulting in an eccentric relative rotation between the inner disks 28 and the outer disks 30. To accomplish this eccentricity in vertical direction, holes 40 and 41 in the respective inner and outer bearing members 27 and 29 are respectively upwardly and downwardly offset so that when the pins 32 and 33 are extended through such holes, the bearing members 27 and 29 will be held in relatively vertically eccentric positions shown in Fig. 3.

50

55

60

As will be perceived in Fig. 1, the sub 22 is provided with a central opening 44 through which rotary mud or drilling fluid may pass from the lower end of a drill pipe into the distributing counterbore or recess 38 in the body 11, a part of such rotary mud or drilling fluid passing downwardly through the central discharge opening 37 so as to be delivered into the well at a point immediately adjacent to the lower portions of the cutting edges provided by the inner disks 28.

65 For properly lubricating and removing cuttings from the outer disks 30 I provide a pair of discharge openings 45 which are directed 70 downwardly and outwardly from the recess 38

in a direction such as indicated by the arrows 46 of Fig. 2 so that jets or streams of the drilling fluid will be delivered outwardly and downwardly against or in front of the forward cutting portions 39 of the cutting edges provided by the outer disks 30. As a result of directing the outlets 45 in the manner previously described, clean or uncontaminated rotary mud is delivered to the downwardly moving portions of the cutting edges of the blades 30, 10 which downwardly moving portions of the cutting edges are at this time entering into cutting engagement with the side walls of the hole being drilled and from thence will move into cutting position with the bottom of the hole. 15

The outer ends of the pins 32 and 33 are provided with cylindrical collars 50 from which squared portions 51 extend, these collars 50 being received in cylindrical recesses 52 at the inner ends of bores 53 formed in the legs 15. 20 The outer portions of the bores 53 are threaded, as indicated at 54, to receive annular externally threaded locking members 55, openings 56 of these locking members being deformed so as to receive a wrench or key by which to screw 25 in and unscrew the locking members. The openings 56 are of such size that the annular members 55 will fit down over the squared projections 51 of the pins 32 and 33. As shown in Fig. 7, the openings 56 may be made polygonal, such as hexagonal, and the key for co-operation therewith to turn the locking members 55 will then be made of corresponding polygonal form. In the assembly of the bit, the pins 32 and 33 are extended through the bearing 35 members 27 and 29 and by engagement by a wrench with the squared projections 51 are rotated in left-hand direction and thereby screwed tightly into the central leg 13. The locking members 55 are then inserted and 40 screwed tightly against the cylindrical collars 50 of the pins 32 and 33, and in this manner lock such pins firmly and positively against becoming loosened and unscrewed from their required 45 positions of operation.

In the smaller sizes of rotary disk bits as illustrated in Fig. 5, the size of the parts employed is not sufficient to permit of the use of the supporting pins 32 and 33 in pairs; therefore, in these small bits a single pin is employed which extends through a single eccentric opening 60 in a bearing member 61. To prevent rotation of the bearing member 61, the shank portion of a pin used in this manner may be fluted or made polygonal, as indicated at 62, the extreme 55 inner end thereof, however, being turned down and threaded, as indicated at 63, so that the desired threaded engagement may be made with the cooperating central leg of the drill bit.

This form of smaller rotary bit is adapted to 60 perform a very efficient cutting operation and, having supporting legs or extensions 13, 14, and 15 integrally formed with the body 11, has no parts which the forces and vibrations 65 encountered during the drilling operation will cause to become unscrewed, displaced, or lost within the well. I have herein shown the invention in simple and operative form, but it is recognized that certain parts or elements are 70 representative of other parts, elements, or structures which may be employed in substantially the same manner to accomplish substantially the same results; therefore, it is to be understood that the invention shall not be limited 75

to the details disclosed herein but shall have the scope set forth in the following claims.

An additional important feature of the invention is the novel means I provide for protecting the inner walls of the leg members 14 and 15 from wear, confining the wear of operation to easily replaceable and relatively inexpensive parts. By reference to Fig. 5 it will be noted that outwardly extending flanges 10 may be formed on the bearing members 27 and 29, there being cooperating counterbores 71 in the outer bores of the rotary cutter disks 28 and 30. In the operation of the bit, the cutting action tends to move the cutters outwardly toward the inner faces of the legs 14 and 15, but the engagement between the flanges 10 of the bearing members 27 and 29 and the counterbores 71 of the cutters 28 and 30 prevents engagement of the outer faces of the cutters with the inner faces of the legs, the wear of operation being between the flanges 10 and counterbores 71 and thus relieved from the inner faces of the legs 14 and 15. The bearing members 27 and 29 and the cutters 28 and 30 are the replaceable elements of the bits and by my improved construction the wear is confined to these replaceable parts.

I claim as my invention:

1. A rotary disk bit of the character described, including: a body having a central, intermediate, and outer legs projecting downwardly therefrom, said legs being of relatively thin, flat form and having the opposing faces thereof parallel so as to provide inner and outer cutter receiving spaces between the flat faces of said legs; right-hand and left-hand pairs of supporting pins, each of said pairs of supporting pins projecting through one of said outer legs, the adjacent intermediate leg, and making threaded engagement with said central leg; inner and outer bearing members supported respectively in said inner and outer spaces by said left-hand and right-hand pairs of pins, said outer bearing members being eccentric to said inner bearing members; inner and outer cutter disks supported respectively on said inner and outer bearing members.

2. A rotary disk bit of the character described, including: a body having a central, intermediate, and outer legs projecting downwardly therefrom, said legs being of relatively thin, flat form and having the opposing faces thereof parallel so as to provide inner and outer cutter receiving spaces between the flat faces of said legs; right-hand and left-hand pairs of supporting pins, each of said pairs of supporting pins projecting through one of said outer legs, the adjacent intermediate leg, and making threaded engagement with said central leg; inner and outer bearing members supported respectively in said inner and outer spaces by said left-hand and right-hand pairs of pins, said outer bearing members being eccentric to said inner bearing members; inner and outer cutter disks supported respectively on said inner and outer bearing members; and locking means for securing said pins in operative position.

3. A rotary disk bit of the character described, including: a body having a central, intermediate, and outer legs projecting downwardly therefrom, said legs being of relatively thin, flat form and having the opposing faces thereof parallel so as to provide inner and outer cutter receiving spaces between the flat faces of said legs;

right-hand and left-hand pairs of supporting pins, each of said pairs of supporting pins projecting through one of said outer legs, the adjacent intermediate leg, and making threaded engagement with said central leg; inner and outer bearing members supported respectively in said inner and outer spaces by said left-hand and right-hand pairs of pins, said outer bearing members being eccentric to said inner bearing members; and inner and outer cutter disks supported respectively on said inner and outer bearing members, there being a central fluid passage extending vertically through said central leg and side fluid passages sloped at such angles as to direct streams of cutting fluid toward the forward portions of the cutting edges of said outer cutting disks.

4. A rotary disk bit of the character described, including: a body having a central, intermediate, and outer legs projecting downwardly therefrom, said legs being of relatively thin, flat form and having the opposing faces thereof parallel so as to provide inner and outer cutter receiving spaces between the flat faces of said legs; right-hand and left-hand pairs of supporting pins, each of said pairs of supporting pins projecting through one of said outer legs, the adjacent intermediate leg, and making threaded engagement with said central leg; inner and outer bearing members supported respectively in said inner and outer spaces by said left-hand and right-hand pairs of pins, said outer bearing members being eccentric to said inner bearing members; inner and outer cutter disks supported respectively on said inner and outer bearing members; and locking means for securing said pins in operative position, there being a central fluid passage extending vertically through said central leg and side fluid passages sloped at such angles as to direct streams of cutting fluid toward the forward portions of the cutting edges of said outer cutter disks.

5. A rotary disk bit of the character described, including: a body having a central, intermediate, and outer legs projecting downwardly therefrom, said legs being of relatively thin, flat form and having the opposing faces thereof parallel so as to provide inner and outer cutter receiving spaces between the flat faces of said legs; right-hand and left-hand pairs of supporting pins, each of said pairs of supporting pins projecting through one of said outer legs, the adjacent intermediate leg, and making threaded engagement with said central leg, said right-hand pair of pins and said left-hand pair of pins being forwardly offset in the direction of rotation of said bit; inner and outer bearing members supported respectively in said inner and outer spaces by said left-hand and right-hand pairs of pins, said outer bearing members being eccentric to said inner bearing members; and inner and outer cutter disks supported respectively on said inner and outer bearing members.

6. A rotary disk bit of the character described, including: a body having a central, intermediate, and outer legs projecting downwardly therefrom, said legs being of relatively thin, flat form and having the opposing faces thereof parallel so as to provide inner and outer cutter receiving spaces between the flat faces of said legs; right-hand and left-hand pairs of supporting pins, each of said pairs of supporting pins projecting through one of said outer legs, the adjacent intermediate leg, and making threaded engagement with said central leg, said

right-hand pair of pins and said left-hand pair of pins being forwardly offset in the direction of rotation of said bit; inner and outer bearing members supported respectively in said inner and outer spaces by said left-hand and right-hand pairs of pins, said outer bearing members being eccentric to said inner bearing members; inner and outer cutter disks supported respectively on said inner and outer bearing members; and locking means for securing said pins in operative position, there being a central fluid passage extending vertically through said central leg and side fluid passages sloped at such angles as to direct streams of cutting fluid toward the forward portions of the cutting edges of said outer cutter disks.

7. A rotary bit of the character described, including: a body having a plurality of legs projecting downwardly therefrom, the opposing faces of said legs being substantially parallel and providing cutter receiving spaces therebetween; pins extending laterally through said legs; relatively inner and outer bearing members supported by said pins in the spaces between said legs in vertically eccentric position, said bearing members having openings therethrough to receive said pins, and the axes of the inner bearing members being downwardly offset relative to the axes of the outer bearing members; and cutters operative on said bearing members, the outer cutters being of larger diameter than the inner cutters.

8. A rotary bit of character described, including: a body having a plurality of legs ex-

tending vertically therefrom, the opposing faces of said legs being flat and providing cutter receiving spaces therebetween; pins extending laterally through said legs; relatively inner and outer bearing members supported on the exposed portion of said pins in such a manner that portions thereof will be exposed to receive bearing members thereon in vertically eccentric position, said bearing members having openings therethrough to receive said pins and the axes of the inner bearing members being downwardly offset relative to the axes of the outer bearing members; and cutters mounted on said bearing members, the outer cutters being of larger diameter than the inner cutters.

9. A rotary bit of the character described, including: a body having outer and inner pairs of legs projecting downwardly therefrom, there being a central leg projecting from said body between the said inner pair of legs, the opposing faces of said legs being substantially parallel and providing cutter receiving spaces therebetween; pins extending laterally through said legs; bearing members supported by said pins in said spaces in vertically eccentric position, said bearing members having openings therethrough to receive said pins, and the axes of the inner bearing members being downwardly offset relative to the axes of the outer bearing members; and cutters operative on said bearing members, the outer cutters being of larger diameter than the inner cutters.
